UNITED STATES PATENT OFFICE.

TONJES A. C. BOTH, OF STRATFORD, CONNECTICUT, ASSIGNOR TO ZEE-SOCKET AND MFG. COMPANY, OF BOSTON, MASSACHUSETTS, A CORPORATION OF MASSACHUSETTS.

ELECTRIC-LIGHT SOCKET.

1,230,848.

Specification of Letters Patent. Patented June 26, 1917.

Original application filed December 30, 1911, Serial No. 668,632. Divided and application filed March 29, 1912, Serial No. 687,184. Divided and this application filed February 20, 1915. Serial No. 9,755.

To all whom it may concern:

Be it known that I, TONJES A. C. BOTH, a citizen of the United States, and a resident of Stratford, in the county of Fairfield and 5 State of Connecticut, but formerly of Malden, in the county of Middlesex and State of Massachusetts, have invented a certain new and useful Electric-Light Socket, of which the following is a specification, taken 10 in connection with the accompanying drawing, which forms a part of the same, this application being a division of my pending application, Serial No. 687,184, filed March 29, 1912, for mechanical movement and electric-light socket, which latter application 15 was a division of my application, Serial No. 668,632, filed December 30, 1911.

My invention relates to electric light sockets and to certain details of construction of 20 the electric light socket, which will be more fully hereinafter described in the specification and pointed out in the claims.

My electric light socket is particularly useful because of its simplicity, the few parts 25 used, and the small space occupied by them and because it makes a quick make and a quick break of the electric current, without arcing, upon the operation of the driving member in either direction.

30 Among other advantages my invention permits the socket to be formed smaller and stronger because the opening in which the operating mechanism is mounted need not be so large as for other switch mechanism.

35 In the accompanying drawing showing illustrative embodiments of my invention and in which the same reference numerals refer to similar parts in the several references,

40 Figure 1 is a transverse horizontal section substantially on the line 1—1 of Fig. 2;

Fig. 2 is a side elevation of my improved electric light socket, partly broken away;

45 Fig. 3 is a side elevation of my electric light socket taken at a right angle to the view of Fig. 2;

Fig. 4 is a side elevation of a modified form of intermediate or hill and valley member; and

50 Fig. 5 is a plan view of the intermediate member illustrated in Fig. 4.

In the illustrative embodiments of my invention shown in the drawing, 1 is an electric light socket including an insulating member 2 formed of a plurality of parts.

Preferably I form the insulating member 2 of two complementary parts 3 and 4, each of them being provided with recesses 5 and 6 to form an interior chamber 7. The recess 6 in the member 3 is provided with two openings 8, 8 to receive the driving members or push buttons 9 and 10. These buttons are provided with shoulders 11, 11 which co-operate with the shoulders 12, 12 in the insulating member 3 to limit the outward 60 movement of the respective driving members or push buttons.

My driven member is preferably a resilient member such as the spring 13 which will be caused to reciprocate with a quick snap 70 within the chamber 7 formed by the two openings 5, 6 in the members 3 and 4. While I may use any suitable form of intermediate movable, or hill and valley member, I preferably use such a member formed out of insulating material such as 14 which is pivoted on the pin 15 and is connected by the pins 16, 16 at its respective ends, to the driving members which as illustrated are push buttons 9 and 10. The pin 15 is preferably 75 journaled in the grooves 37, 37 on the insulating member 3.

By pushing in the driving member or push button 9, the intermediate movable hill and valley member 14 will be caused to rock 85 upon its pin 15 and will store up the power in the driven resilient member 13 until such time as the kicker or accelerator 17 crowds or pushes the end 18 of the resilient driven member 13 out of the valley 19 and over the 90 ledge 20 when the entire resilient member 13 will snap over with a quick snap and make a connection between the screw shell contact 21, Fig. 2, carried by the screw shell 22 and the contact 23 of the binding post 24 95 carrying the binding screw 25. When it is desired to disconnect the consuming device, it is merely necessary to depress the driving member or push button 10 which will have then been elevated. Alternate pressure upon 100 the driving members or push buttons, whichever push button is for the moment extended, will cause the resilient driven member 13 to alternately snap into and out of contact with the contacts 21 and 23.

105 The binding post 26 is provided with an arm 27 which is the center contact for the consuming device. This binding post 26 is provided with a binding screw 28 and is held to the insulating member 3 by means of 110

the locking screw 29. The binding post 24 is secured to the insulating member 4 by the locking screw 30 which is passed through the insulating members in the opposite direction from the locking screw 29. In this manner the insulating members are secured together at the same time that these screws secure the binding post to the insulating members. This same operation will also secure the screw shell 22 to the insulating members 3 and 4 by holding the dovetail surfaces 31 on the insulating members in contact with the dovetail 32 on the screw shell 22.

The intermediate member 14 I preferably form in any suitable manner out of some insulating material as porcelain so as to insulate the driven member 13 from the push buttons 9 and 10 permitting them to be formed out of metal or conducting material without being provided with an insulating operating surface.

I may, however, in some cases make this intermediate member out of metal. In Fig. 4 I have shown an intermediate member as made from a stamping and provided with the valleys 34, 34 each valley having a ledge 35. Associated with each valley is also preferably an accelerator or kicker 36 to crowd or kick the operating end of the resilient driven member 13 out of the valley, upon the intermediate movable member reaching a certain predetermined position, thereby permitting the operating end of the spring to fly from one valley to the other and at the same time cause the entire resilient member to move laterally with a quick and positive snap.

I also preferably provide the intermediate member with the trunnions 38, 38 to be received in the grooves 37, 37 in the insulating member 2 which forms a bearing for the intermediate member.

My invention converts a slow or fast pressure on the raised driving member into a quick and positive reciprocating movement of the resilient driven member 13. The switch mechanism serves to make a quick make and a quick break of the electric current without arcing, upon operating the push buttons.

My push buttons, it will be noted, are located on the same side of the socket and adjacent to each other forming a strong mechanical structure and one which can be readily operated with the minimum inconvenience. This arrangement of the push buttons is also quite pleasing to the eye.

My improved socket is adapted to be used without the usual socket shell and cap, though I preferably surround my socket with such a shell and cap. As these, however, are no part of my present invention, I have omitted them from the drawing.

It would be possible in some cases to use only one push button or driving member

which would be pushed in the ordinary manner. It would be moved in the other direction by pulling on it in any suitable manner as by grasping it by the thumb and finger. My invention, therefore, includes either one or more push buttons for actuating the intermediate member. Preferably, I use two such push buttons, as shown.

Having thus described this invention in connection with illustrative embodiments thereof to the details of which I do not desire to be limited, what is claimed as new and what it is desired to secure by Letters Patent is set forth in the appended claims:

1. In electric light sockets, the combination of an insulating base, one or more push buttons mounted in the base, a resilient compression driven member, and an intermediate member provided with a substantially flat face and with a groove or valley at either end of said face, said grooves or valleys adapted to momentarily hold the resilient compression driven member from movement, said intermediate member adapted to be actuated by the push button or buttons. 90

2. In electric light sockets, the combination of an insulating base, one or more push buttons mounted in the base, a resilient conducting compression driven member, and an intermediate member provided with a substantially flat face and with a groove or valley at either end of said face, said grooves or valleys adapted to momentarily hold the resilient conducting compression driven member from movement, said intermediate member adapted to be actuated by the push button or buttons. 100

3. In electric light sockets, the combination of an insulating base, one or more push buttons mounted in the base, a resilient conducting compression driven member, and an intermediate insulating member provided with a substantially flat face and with a groove or valley at either end of said face, said grooves or valleys adapted to momentarily hold the resilient conducting compression driven member from movement, said intermediate member adapted to be actuated by the push button or buttons. 110

4. In electric light sockets, the combination of an insulating base, one or more push buttons, a sliding resilient conducting driven member adapted to slide on the insulating base, and an intermediate member provided with grooves or valleys to coöperate with the resilient conducting driven member, said intermediate member adapted to be actuated by the push button or buttons. 120

5. In electric light sockets, the combination of an insulating base, one or more push buttons, a sliding resilient conducting driven member adapted to slide on the insulating base, and an insulating intermediate member provided with grooves or valleys to coöperate with the resilient conducting driven member. 125

member, said intermediate member adapted to be actuated by the push button or buttons.

6. In electric light sockets, the combination of an insulating base, one or more push buttons, a sliding resilient conducting driven member adapted to slide on the insulating base and an intermediate pivoted member provided with grooves or valleys to coöperate with the resilient conducting driven member, said intermediate pivoted member adapted to be actuated by the push button or buttons.

7. In electric light sockets, the combination of an insulating base, one or more push buttons mounted in the insulating base, a sliding resilient compression driven member adapted to slide bodily upon the insulating base, and an intermediate member adapted to be actuated by the push button or buttons and provided with means to momentarily hold the sliding resilient compression driven member from movement.

8. In electric light sockets, the combination of an insulating base, one or more push buttons mounted in the insulating base, a sliding resilient compression driven member adapted to slide bodily upon the insulating base, and an intermediate member adapted to be actuated by the push button or buttons and provided with means to momentarily hold the sliding resilient compression driven member from movement and with additional means to positively overcome the holding action of the first means when the intermediate member has reached a certain predetermined position.

9. In electric light sockets, the combination of an insulating base, one or more push buttons mounted in the insulating base, a sliding resilient compression driven member

adapted to slide upon the insulating base, and an intermediate insulating pivoted member adapted to be actuated by the push button or buttons and provided with means to momentarily hold the sliding resilient compression driven member from movement.

10. In electric light sockets, the combination of an insulating section having two adjacent openings for two push buttons and provided with surfaces to limit the movement of the push buttons in one direction, push buttons mounted in the adjacent openings and provided with surfaces to coöperate with the surfaces carried by the insulating section, a pivoted intermediate member provided with means to coöperate with a resilient driven member, means to connect the push buttons to the intermediate member, a resilient driven member independent of the intermediate member and adapted to have movement with relation to it, and spaced electrical contacts adapted to be bridged by the resilient driven member.

11. In electric light sockets, the combination of an insulating base, one or more push buttons, a resilient conducting driven member and an intermediate member provided with a substantially flat face, and with means at either end of the flat face to hold the resilient driven member from movement during a portion of the operating of the intermediate member, and also with means to subsequently positively actuate the resilient driven member when the intermediate member has reached another position in its travel.
